W. J. Field, Attorney.

UNITED STATES PATENT OFFICE.

GEORGE HENRY PARKER, OF ARLINGTON, NEW JERSEY, ASSIGNOR TO JOHN WALLACE
BAKER, OF STAMFORD, CONNECTICUT.

STOP DEVICE FOR SLIDING SASHES.

No. 889,484.

Specification of Letters Patent.

Patented June 2, 1908.

Application filed February 2, 1906. Serial No. 299,109.

To all whom it may concern:

Be it known that I, GEORGE HENRY PARKER, residing at Arlington, in the county of Hudson and State of New Jersey, have invented certain new and useful Improvements in Stop Devices for Sliding Sashes, of which the following is a full, clear, and exact description, such as will enable others skilled in the art to which it appertains to make and 10 use the same.

My invention relates to safety devices for windows and has for its principal object to provide a simple and effective device whereby a window sash, or similar movable member, may be permitted to be opened to a limited extent, and then positively held against further opening thereafter.

Another object thereof is to provide means for positively locking a stop device employed 20 to limit the relative opening movement of sashes, so that tampering with said device from the outside will be prevented.

Other objects will be in part obvious and in part pointed out hereinafter.

25 The invention accordingly consists in the features of construction, combinations of elements and arrangement of parts which will be exemplified in the construction hereinafter described and the scope of the application of which will be indicated in the following claims.

In the accompanying drawing, wherein is illustrated one of several various embodiments of my invention, Figure 1 is a view in 35 perspective, showing a pair of coöperating stop devices mounted upon relatively movable sashes, Fig. 2 is a similar view of the movable stop. Fig. 3 is a similar view of the guide for the movable stop. Fig. 4 is a similar view of the locking screw for the movable stop. Fig. 5 is a view in elevation of the 40 fixed stop mounted upon one of the sashes.

Similar reference characters refer to similar parts throughout the several figures of the 45 drawing.

Although it is thought that the ends and objects sought to be attained will be clearly understood without further discussion before entering into a detailed description of 50 the structural features thereof, it may be well to bring to notice that my invention, as herein disclosed, has special relation to means for allowing relative movement of 55 slideable sashes to a limited extent only, as, for instance, to afford ventilation, the ar-

angement being such that the sashes, when opened a predetermined amount, cannot be further opened or the stop devices manipulated by an outside intruder.

Referring now to the drawings, 1 represents the lower and 2 the upper sash, both of which are slidably mounted for free relative movement in the frame 3, as is usual in window construction, and are provided with suitable suspending means, as cord 4, shown 60 as one of the supports of sash 1. The term "sash", as used throughout this specification and claims, is intended to include any sliding member adapted, when in its normal position, to close an opening in a wall. The 65 upper meeting rail 5 of sash 1 has secured thereto, near one end, by suitable means, as screws 6, a hollow guide 7, which may be stamped or formed from a single strip of sheet metal, the lower edges thereof being 70 preferably slightly separated to provide a guiding slot 8. Guide 7 is provided in its upper wall, with a longitudinally-extending slot 9 having substantially parallel walls for a portion of its extent, which lead into an 75 enlarged, substantially circular opening 10 in its forward portion, the slot being of substantially "key-hole" form.

Incased within guide 7 and adapted to slide therein is a stop 11 having a depending 80 kerf or ridge 12 in engagement with the walls of slot 8, the lower surface of which comes substantially flush with the lower surface of guide 7 and rests in contact with the meeting rail. Stop 11 in its forward end has an open-ended, vertical, slotted extension 12', the 85 side members of which form posts 13 that have their free ends rounded, as at 14. Between posts 13 of vertical extension 12 is provided a way 15. Extending downwardly 90 through slot 9 of guide 7 is a screw 16, the threaded end of which threads into an opening 17 in stop 11, and this screw is further provided with an enlargement or shoulder 18 intermediate the ends thereof, the diameter 95 of which is greater than the width of the narrow portion of slot 9, but is, however, of such size as readily to pass through circular opening 10 of said slot.

Mounted upon side rail 19 of upper sash 2 100 at a point a short distance from the lower end thereof, is a fixed stop 20, which is vertically disposed above stop 11 and is designed to co-operate therewith, said fixed stop being herein shown as comprised by a headed screw 110

driven into side rail 19. An encircling collar resting against side rail 19 provides a space between the head of screw 20 and said collar.

5 Although from the foregoing description, the operation of my invention should be largely apparent, it may be noted that normally slideable stop 11 is in a retracted position in guide 7, being held in such position by 10 means of screw 16, which clamps the said stop between the upper wall of guide 7 and shoulder 18 of said screw. With stop 11 in this position, no limitation whatever is put upon the relative movement of the sashes.

15 When, however, it is desired to limit the relative movement of the sashes, as, for example, to provide for ventilation, it is only necessary to loosen screw 16 and, by grasping said screw, stop 11 may be slid in guide 7 to an 20 extended position, when the vertical extension thereof will be in the path of stop 20 secured to sash 2. Screw 16 may then be turned and shoulder 18 passing through opening 10 in slot 9 of guide 7 will lock the 25 same positively against movement. Now, when sash 2 is raised or sash 1 lowered, stops 20 and 11 will co-act and the shaft of stop 20 will pass between posts 13 of extension 12 and the head thereof, taking along the inner 30 surfaces of said posts, comes into engagement with the horizontal portion of stop 11, when further opening movement of either or both of the sashes will be prevented. Stops 11 and 20 being thus in an interlocked condition, and stop 11 being firmly and positively 35 locked against retraction, manipulation from the outside is impossible. The sashes, or one of them, being permitted to open but to a limited extent, it will also be impossible for a 40 person without the window to enter therethrough or reach the stop devices from the outside. Moreover, as the head of fixed stop 20 engages the inside wall of posts 13, unlocking thereof cannot be effected by a person 45 outside inserting a jimmy or other prying instrument between the meeting rails of the sashes.

It will thus be apparent that I have provided a construction well adapted to attain 50 the objects of my invention, such that, while

the sashes are normally afforded free relative movement, the stop devices may be easily manipulated effectively to limit the relative movement thereof. The device, moreover, possesses but few parts, is cheap to 55 manufacture and does not detract from the sightliness of the window structure.

It should be obvious that, while the device is particularly well adapted for the use hereinbefore described, it may be as well used in 60 other analogous relations and yet retain its inherent advantages.

As many changes could be made in the above construction and many apparently 65 widely different embodiments of my invention could be made without departing from the scope thereof, I intend that all matter contained in the above description or shown in the accompanying drawings shall be interpreted as illustrative and not in a limited 70 sense.

I desire it also to be understood that the language used in the following claims is intended to cover all of the generic and specific 75 features of the invention herein described and all statements of the scope of the invention, which, as a matter of language, might be said to fall therebetween.

Having described my invention, what I claim as new and desire to secure by Letters 80 Patent is:—

In combination, a pair of sliding sashes, a casing secured to the upper rail of one of said sashes, a bolt mounted to slide in said casing having at one end a pair of upwardly extending 85 posts, said posts having outwardly inclined end portions, a headed member located upon the other sash adapted to be received between said posts and be guided therebetween by said outwardly inclined portions, and a locking screw adapted to slide said bolt 90 and lock the same in an extended or retracted position.

In testimony whereof I affix my signature, in the presence of two witnesses.

GEORGE HENRY PARKER.
